C. L. GOODRUM,
TELEPHONE EXCHANGE SYSTEM,
APPLICATION FILED SEPT. 11, 1916.

1,251,768.

Patented Jan. 1, 1918.

UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,251,768.

Specification of Letters Patent.

Patented Jan. 1, 1918.

Application filed September 11, 1916. Serial No. 119,508.

To all whom it may concern:

Be it known that I, CHARLES L. GOODRUM, a citizen of the United States, residing at Brooklyn, in the county of Kings and State 5 of New York, have invented certain new and useful Improvements in Telephone-Exchange Systems, of which the following is a full, clear, concise, and exact description.

This invention relates to telephone 10 exchange systems requiring machine switching and is particularly adapted for use in a large system where a connection may lead over a relatively great number of what are known as selector or trunk-hunting switches.

15 It frequently happens that, after the calling subscriber has, by means of the directive impulses of his calling dial, built up a connection including a relatively large number of these selectors, it is found that the desired 20 line at the connector is busy. Heretofore, in such event, the calling subscriber received a busy signal and had to replace his receiver, whereupon the said switches were all automatically restored to their normal positions.

25 The object of the present invention is the provision of means which will make it unnecessary to release a connection when the desired line at the connector is busy. In the present embodiment of the invention, when 30 the switch finds that the desired line is busy, it will wait in operative relation to such line under the control of an impulse device. When the desired line becomes idle, the subscriber, by again operating the calling 35 dial, may be placed in talking relation with the desired line.

The drawing represents diagrammatically 40 a telephone system employing the present invention. The finder and selector switches of this system have been indicated by fixed terminals and brushes which are of a type 45 commonly employed in these switches.

It is believed that the present invention 50 will best be described by tracing a connection over the system.

Referring to the drawings, A represents the substation apparatus of a calling subscriber. When the subscriber at A removes his receiver from the switchhook, brushes 55 b and b' of a finder engage terminals t and t' of the calling subscriber's line and extend this line over conductors c^2 and c^3 to brushes b^2 and b^3 of a selector. The subscriber on 60 operating the dial, places these brushes b^2 and b^3 in engagement with the terminals t^2 and t^3 of the trunk line leading to the desired connector switch.

When the calling line has been extended to the connector, stepping relay 1 is energized over a circuit which may be traced 60 from grounded battery, stepping relay 1, terminal t^3 , brush b^3 , conductor c^3 , brush b' , terminal t' , conductor c' , substation apparatus A, conductor c' , terminal t , brush b , conductor c^2 , brush b^2 , terminal t^2 , right-hand 65 winding of relay 1, to ground. Relay 1 is thereupon energized and attracts its armature. This closes a circuit for slow release relay 2, which may be traced from grounded battery, relay 2, front contact and armature 70 of relay 1, to ground. Relay 2 attracts its armatures. When the calling subscriber operates his calling dial or impulse sender 37, stepping relay 1 is momentarily deenergized, but relay 2, which is slow to deenergize, holds 75 up its armatures during these interruptions in its energizing circuit. In response to these directive impulses, the switch brushes are stepped to the desired groups by the primary magnet 7 which is energized over a 80 circuit extending from grounded battery, magnet 7, wiper 9, front contact and armature of relay 2, back contact and armature of relay 1 to ground. At the first interruption of stepping relay 1, a second slow release relay 3 is energized over a circuit which may be traced from grounded battery, relay 3, front contact and right-hand armature of 85 relay 2, back contact and armature of relay 1, to ground. Relay 3 attracts its armatures 90 and completes a circuit for escape magnet 4, which may be traced from grounded battery, magnet 4, back contact and left-hand armature of slow release relay 5, wiper 6 in its first position, front contact and left-hand 95 armature of slow release relay 3, front contact and left-hand armature of relay 2, to ground. At the termination of the first series of directive impulses, relay 1 attracts its armature and thereby interrupts, at its 100 back contact, the energizing circuit for the second slow release relay 3. When relay 3 deenergizes, it interrupts, at its front contact and left-hand armatures, the energizing circuit of the escape magnet 4. This 105 magnet deenergizes and moves the side-switch wipers into their second position.

Thereupon the calling subscriber sends another series of directive impulses, and relays 2, 3, and 4 are energized as above described. 110

The secondary stepping magnet 8 is energized over a circuit which may be traced from grounded battery, stepping magnet 8, wiper 9 in its second position, front contact 5 and right-hand armature of relay 2, back contact and armature of relay 1, to ground.

At the termination of these impulses, relay 1 again attracts its armature and also interrupts, at its back contact, the energizing circuit for relay 3. Relay 3 then de-energizes and interrupts, at its front contact and left-hand armature, the energizing circuit for escape magnet 4. Escape magnet 4 thereupon de-energizes and moves the side-switch wipers into position 3, even when the desired line is busy.

If the desired line is idle, the escape magnet is energized over a circuit which may be traced from grounded battery, escape magnet 4, back contact and armature of relay 5, side-switch wiper 6 in its third position, conductor 10, back contact and armature of relay 11, conductor 12, back contact and right-hand armature of relay 3, front contact and left-hand armature of relay 2, to ground. Escape magnet 4 attracts its armatures and at its innermost armature completes a circuit over which ringing current is applied. This circuit extends from grounded battery, generator 13, relay 5, front contact and innermost right-hand armature of magnet 4, conductor 14, right-hand winding of relay 15, side-switch wiper 16 in its third position, connector brush 17, substation apparatus B, over the upper side of the line, brush 18, side-switch wiper 19 in its third position, conductor 20, conductor 10, side-switch wiper 6 in its third position, back contact and armature of relay 3, escape magnet 4, to ground. When the called party at B removes his receiver, the marginal relay 5 of this circuit is energized and interrupts the energizing circuit of escape magnet 4, whereupon the side-switch wipers move into the fourth or talking position and the desired connection is established between substations A and B.

If, however, the desired line is busy, this condition will be characterized by ground connection on test terminal 21 of the desired line. Relay 11 will then be energized over a circuit extending from grounded battery, right-hand winding of relay 11, side-switch wiper 22 in its second position, brush 23, 55 and grounded test terminal 21. Relay 11 thereupon attracts its armatures and, at its left-hand armature establishes a locking circuit for itself extending from grounded battery, left-hand winding, front contact and armature of relay 1, conductor 12, right-hand armature and back contact of relay 3, left-hand front contact and armature of relay 2 to ground. When the side-switch wiper moves into third position at the close 60 of the last series of directing impulses, a

locking circuit for relay 11 is established from grounded battery, front contact 24 and its right-hand armature, side-switch wiper 22 in its third position, brush 23 and grounded test terminal 21. This locking circuit 70 is maintained as long as the desired line remains busy. When relay 11 was energized, it also attracted its left-hand armature, which it locked up over a circuit from grounded battery, left-hand winding of relay 11, left front contact and armature of this relay, conductor 12, back contact and right-hand armature of relay 3, front contact and left-hand armature of relay 2, to ground.

Here it will be noted that, as 80 long as the left-hand armature of relay 11 is attracted, the energizing circuit for escape magnet 4 is open and its side-switch wipers will continue to remain in their third position. While the desired line is busy, busy 85 tone is applied to the calling line as follows: grounded battery, secondary winding of induction coil 29, side-switch wiper 30 in its third position, back contact and outermost right-hand armature of escape magnet 4, conductor 31 and the upper side of the line to substation A. The interrupter 28, by means of the primary winding of induction coil 29, induces an alternating current in the circuit just described. When, however, the 90 desired line becomes free the locking circuit through the right-hand winding of relay 11 is broken, but the energizing circuit for escape magnet 4 is still maintained open at the left-hand armature of relay 11. In order 100 to complete the energizing circuit of the escape magnet 4, it is necessary to bring about the de-energization of the left-hand winding of the relay 11. This is brought about by the waiting party. The waiting 105 party in order to complete the connection with the desired line must transmit, after the desired line becomes idle, one or more impulses in addition to the directive impulses which he has previously transmitted. 110 These impulses cause stepping relay 1, which has previously been energized, to retract its armature. This completes an energizing circuit for slow release relay 3 over a circuit previously described. Relay 3 is energized and, at its back contact and right-hand armature, opens the circuit which was previously described as extending through the left-hand winding of relay 11. As soon 115 as relay 3 was energized, it attracted its outermost left-hand armature and completed an energizing circuit for slow release relay 25, which may be traced from grounded battery, relay 25, front contact and outermost left-hand armature of relay 3, side-switch wiper 120 26 in its third position, conductor 27, front contact and armature of relay 1, to ground. When relay 25 was energized, it completed a parallel locking circuit for the left-hand armature of relay 11, which may be traced 125 130

130 of the last series of directing impulses, a

- from grounded battery, left-hand winding of relay 11, front contact and armature of relay 11, conductor 12, front contact and armature of relay 25, to ground. It should here be added that a brief interval of time exists between the energization of relays 3 and 25, during which interval the left-hand armature of relay 11 falls off, if the called line is now idle, and completes the circuit 5 for the escape magnet, which circuit was previously described. Escape magnet 4 then attracts its innermost left-hand armature and ringing current is applied to the called party's line. When subscriber B responds by 10 removing his receiver, the energizing circuit for escape magnet 4 is interrupted at marginal relay 5, which causes the side-switch wipers to move into position 4, as previously described.
- 15 It will be noted that no signal is transmitted to the waiting party to inform him when the desired line becomes idle. It will be understood, however, that such a signal may be employed if desired. The absence of 20 the signal to inform the waiting party that the desired line is free prevents the possibility of a double connection in case two or more parties were awaiting connection with the same line, since it would be unusual 25 for two waiting parties to dial at the same time. Under the present condition, subscribers may be instructed to operate their dials at intervals as long as the busy tone is continued.
- 30 At the termination of the conversation, the calling party at A replaces his receiver, which action causes relay 1 to be deenergized. Release magnet 32 receives an energizing impulse over the following circuit: 35 grounded battery, magnet 32, off-normal contact 33, conductor 34, back contact and right-hand armature of relay 2, back contact and armature of relay 1, to ground. Magnet 32 completes the following locking circuit for 40 itself: from grounded battery, magnet 32, off-normal contact 33, armature and front contact of magnet 32, to ground. The switches indicated by their brushes 35 and 45 36 and utilized in establishing the connection to the connector are restored to their normal positions by similar release magnets and circuits which are familiar to those skilled in the art and are not herein shown or described.
- 50 It will be understood that the device herein described and illustrated is capable of many variations and applications and that the scope of this invention is limited only by the appended claims.
- 55 What is claimed is:
1. In a telephone system, a plurality of incoming lines, an outgoing line, a selectively operable switching device for extending any one of said incoming lines to the outgoing line, an impulse device for controlling the setting of said switch, an escape magnet, a circuit for actuating said magnet, a relay, and a locking circuit for controlling said
- line, an impulse device for controlling the setting of said selectively operable switching device, and means for retaining said switching device under the control of said impulse device after it has been set on to the outgoing line. 65
2. In a telephone system, incoming lines, an outgoing line, a switch for extending any of said incoming lines to said outgoing line, a relay controlling, upon its actuation, the seizure of the outgoing line by the switch, 70 and means jointly controlled over an incoming line and the outgoing line for actuating said relay.
3. In a telephone system, incoming lines, an outgoing line, a switch for extending any one of said incoming lines to said outgoing line, a relay controlling, upon its actuation, the seizure of the outgoing line by the switch, means jointly controlled and successively actuated, first over an outgoing line 75 and then over the incoming line for actuating said relay.
4. In a telephone system, incoming lines, an outgoing line, a switch for extending any one of said incoming lines to said outgoing line, a relay controlling, upon its deenergization, the seizure of the outgoing line by the switch, and means jointly controlled over an incoming and the outgoing line for actuating said relay. 80
5. In a telephone system, incoming lines, an outgoing line, a switch for extending any one of said incoming lines to said outgoing line, a relay controlling, upon its deenergization, the seizure of the outgoing line by the switch, and means jointly controlled and successively actuated, first over an outgoing line 85 and then over the incoming line for actuating said relay.
6. In a telephone system, incoming lines, an outgoing line, a switch for extending any one of said incoming lines to said outgoing line, a relay controlling, upon its actuation, the seizure of the outgoing line by said switch, said relay having two windings, and locking circuits including said windings, one of said circuits being controlled over said incoming line and the other circuit being controlled over said outgoing line. 90
7. In a telephone system, incoming lines, an outgoing line, a switch for extending any one of said incoming lines to said outgoing line, an escape magnet, a circuit for actuating said magnet, and a relay controlled over said outgoing line and one of said incoming lines for controlling said circuit. 100
8. In a telephone system, incoming lines, an outgoing line, a switch for extending any one of said incoming lines to said outgoing line, an impulse device for directing the setting of said switch, an escape magnet, a circuit for actuating said magnet, a relay, and a locking circuit for controlling said 105
- 110
- 115
- 120
- 125

- escape magnet including the winding of said relay and jointly controlled over said outgoing line and over said incoming line.
9. In a telephone system, incoming lines, 5 an outgoing line, a switch for extending any one of said incoming lines to said outgoing line, an impulse device for directing the setting of said switch, and means under the control of said impulse device for maintaining said switch in operative relation to said outgoing line if that line is busy.
10. In a telephone system, incoming lines, an outgoing line, a switch for extending any one of said incoming lines to said outgoing line, an impulse device for directing the setting of said switch, and means including a circuit under the control of said impulse device for maintaining said switch in operative relation to said line if that line is busy 15 and for actuating said switch to seize said line when it becomes idle.
11. In a telephone system, incoming lines, an outgoing line, a switch for extending any one of said incoming lines to said outgoing line, an impulse device for directing the setting of said switch, and means including a locking circuit under the control of said impulse device for maintaining said switch in operative relation to said line while it is 20 busy and for actuating said switch to seize said line when it becomes idle.
12. In a telephone system, incoming lines, an outgoing line, a switch for extending any one of said incoming lines to said outgoing 25 line, an impulse device for directing the setting of said switch, and means including two locking circuits in parallel which are jointly controlled by the condition of the desired line and by said impulse device for maintaining said switch in operative relation to said line while it is busy and to permit said line to be seized when it becomes idle.

line, an impulse device for directing the setting of said switch, and means for controlling the seizure of said outgoing line by said switch including a locking circuit completed when said line is busy and opened by any actuation of the impulse device after 35 the busy condition is removed.

13. In a telephone system, incoming lines, an outgoing line, a switch for extending any one of said incoming lines to said outgoing line, an impulse device for directing the setting of said switch, and means including a locking circuit having parallel branches which may be successively closed for maintaining said switch in operative relation to said outgoing line while it remains busy and 40 for permitting one waiting incoming line to be connected to said line.

14. In a telephone system, incoming lines, an outgoing line, a switch for extending any of said incoming lines to said outgoing line, 45 an impulse device for directing the setting of said switch, and means including two locking circuits in parallel which are jointly controlled by the condition of the desired line and by said impulse device for maintaining said switch in operative relation to said line while it is busy and to permit said line to be seized when it becomes idle.

In witness whereof, I hereunto subscribe my name this 8th day of September, A. D. 65 1916.

CHARLES L. GOODRUM.
